UNITED STATES PATENT OFFICE.

GEORGE W. HORNE, OF SAN FRANCISCO, CALIFORNIA, ASSIGNOR TO
WILLIAM IRELAN, SR., OF SAME PLACE.

CASTER.

SPECIFICATION forming part of Letters Patent No. 242,648, dated June 7, 1881.

Application filed April 5, 1881. (No model.)

To all whom it may concern:

Be it known that I, GEORGE W. HORNE, a subject of the Queen of Great Britain, residing at San Francisco, in the county of San Francisco and State of California, have invented certain new and useful Improvements in Furniture-Casters; and I do hereby declare the following to be a full, clear, and exact description of the invention, such as will enable others skilled in the art to which it appertains to make and use the same, reference being had to the accompanying drawings, and to the letters or figures of reference marked thereon, which form a part of this specification.

15 My invention relates to furniture-casters; and it consists in the construction and arrangement of devices, as hereinafter more fully described and claimed.

In the annexed drawings, in which like letters indicate like parts in the several views, Figure 1 is a plan view of the under surface of the caster, partly in section and with the under ring removed. Fig. 2 is a section on the line *x x*. Fig. 3 is a view of the upper surface 25 of the center ring or plate; and Fig. 4 is a view of the under surface of the upper plate with lower ring attached.

The body of the caster consists of a flanged plate, A, having a stem or pintle, A'. This plate is provided on its under surface with recessed lugs *a a*, that are cast against the inner side of the flange *a'*, and form wedge-shaped bearings for the journals of the rollers B. These rollers are made tapering toward each 35 end, and are supported by their journals *b* in the bearings *a a*. When in position the rollers are held in place by the lugs or caps *c c* on the ring C. After the ball D is put in position it is secured by the ring E, which is connected 40 with the upper flanged plate, A, by bent arms *e e e*, that are fastened thereto by screws *d*. These arms also hold the ring C in place.

This caster is particularly adapted for use on piano-legs and other heavy articles of furniture.

The arrangement of the rollers B, which are 45 preferably five in number, is such that friction of the same with the surface of the ball D is greatly diminished and the operation of the parts rendered more easy and efficient than when a greater or less number of the rollers are 50 employed. The rollers are also superior to wheels, as they will revolve freely, whatever the direction may be in which the caster is moved.

The frame of the caster may be made of any 55 suitable metal, in two or more castings, as desired, the center ring, C, being cast separately or in connection with the ring E and arms *e*, as found convenient.

If desired, the ring E may be dispensed with, 60 the ball D being then held in place by the bent arms *e* alone, which, in that case, may be cast either upon the plate A or ring C. By employing the ring E, however, a better effect is produced, as the arms *e* are thereby strengthened, 65 and their lower ends prevented from becoming entangled with or abrading the carpet or other surfaces over which the caster is rolled.

The caster is preferably attached to the furniture by means of a stem or pintle in the 70 usual manner; but the pintle may be dispensed with and the caster attached by screws passing through the plate A.

Having thus described my invention, what I claim as new, and desire to secure by Letters 75 Patent, is—

The combination of the flanged plate A, having bearings *a*, rollers B, center ring, C, provided with caps *c*, ball D, lower ring, E, and bent arms *e*, substantially as shown and described.

In testimony whereof I affix my signature in presence of two witnesses.

GEORGE WILLIAM HORNE.

Witnesses:

WILLIAM IRELAN, Sr.,
OTIS V. SAWYER.
